F. STILLWELL

WINDOW GLASS MOUNTING

Filed June 28, 1922

Inventor

Frank Stillwell

By his Attorney

Edgar Dantes

UNITED STATES PATENT OFFICE.

FRANK STILLWELL, OF BROOKLYN, NEW YORK.

WINDOW-GLASS MOUNTING.

Application filed June 28, 1922. Serial No. 571,449.

To all whom it may concern:

Be it known that I, FRANK STILLWELL, a citizen of the United States, and residing at Brooklyn, in the county of Kings and State of New York, have invented certain new and useful Improvements in Window-Glass Mountings, of which the following is a specification, such as will enable those skilled in the art to which it appertains to make and use the same.

This invention relates to the mounting of transparent panels in connection with window sashes and the like, and the object of the invention is to provide means for holding said transparent panels in position and for reinforcing the usual sealing body commonly employed for this purpose to increase the life of said body; and with this and other objects in view the invention consists in a device of the class and for the purpose specified which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a sectional view through part of a window sash showing one form of my improvement mounted in connection therewith;

Fig. 2 a plan view of the blank from which the device shown in Fig. 1 is made;

Fig. 3 a view looking in the direction of the arrow 3 of Fig. 1 with part of the construction broken away;

Fig. 4 a view similar to Fig. 1 showing a slight modification; and,

Fig. 5 a plan view of a blank from which the device shown in Fig. 4 is made.

In Figs. 1 and 3 of the drawing, I have shown for the purpose of illustrating one use of my improvement, a window sash 10 provided with the usual groove 11 for receiving the transparent panel or window-pane 12 and, in practice, I employ a strip 13 of thin sheet metal cut out to form on one side edge thereof a plurality of elongated finger-like members 14 and on the other side thereof with spaced prong members 15, which are preferably arranged in line with one of a number of finger members 14 and,

in practice, the strip 13 is bent into substantially V-shaped formation in cross section by bending the finger members 14 at an angle to the body of the strip as clearly shown in Fig. 1 of the drawing, and in the use of my improved device a strip of the desired length is cut and placed in juxtaposition to the panel 12, when said panel is in position, and the prongs 15 are driven into one of the rails of the sash 10 as shown in said figure. This is done both in the top and bottom and side rails of the sash, after which the usual body of putty 16 is placed in position in the usual manner, and this body of putty passes through the fingers 14 and around the strip 13, and said strip and the fingers thereof are completely imbedded in the putty when this operation is completed, and the finger members 14 will serve to hold the body of putty 16 together against cracking and breaking away from the panel 12, which eventually would loosen the panel or cause a leak between the panel and the separate rails of the sash and will also cause the rotting of the rails of the sash.

With the construction shown in Figs. 1 to 3 inclusive the members 14 by reason of their construction will be capable of spring action to allow for the slight expansion and contraction of the body of putty 16, but in Figs. 4 and 5 of the drawing, I have shown said finger members 14 provided with pointed ends 14a which are adapted to be driven into the rails of the window sash to reinforce said finger members and to hold the same approximately in predetermined positions.

My improved device may be made up very cheaply and may be quickly and easily mounted in connection with a suitable window sash and will take the place of the usual V-shaped panel retainers commonly employed in window constructions of this class and will materially lengthen the life of the putty body employed, the same operating to hold said body of putty against chipping or breaking away from the rails of the window sash as well as from the panel 12.

It will be understood that while I have shown one use of my improvement, that I am not necessarily limited to this use, nor am I limited to the specific arrangement of the prongs 15, or the members 14 of the strip, and various changes therein and modifications thereof may be made, within

the scope of the appended claims, without departing from the spirit of my invention or sacrificing its advantages.

Having fully described my invention, what I claim as new and desire to secure by Letters Patent, is;—

1. A device of the class described comprising a strip of sheet metal provided at one side edge with spaced prongs and at 10 the opposite side edge with spaced independent members, all portions of the strip lying in the same plane, and said spaced members being adapted to be bent at an angle to the remainder of the strip in the 15 use thereof.

2. A device for retaining window panels in position in a window sash and for reinforcing the putty body employed, said device comprising a strip of sheet metal provided 20 at one side edge with spaced prongs and at the opposite side edge with spaced independent members, all portions of the strip lying in the same plane, the prongs of said strip being adapted to be forced into the 25 sash rails with the strip proper in juxtaposition to and bearing upon the panel, and the members of said strip being adapted to be bent at an angle to the strip and embedded in the body of putty.

3. A device for retaining window panels 30 in position in a window sash and for reinforcing the putty body employed, said device comprising a strip of sheet metal provided at one side edge with spaced prongs and at the opposite side edge with spaced 35 independent members, all portions of the strip lying in the same plane, the prongs of said strip being adapted to be forced into the sash rails with the strip proper in juxtaposition to and bearing upon said panel, 40 the members of said strip being adapted to be bent at an angle to the strip and embedded in the body of putty and the free ends of said members being pointed and adapted to be forced into the sash rails. 45

4. A device of the class described comprising a strip of sheet metal provided at one side edge with spaced prongs and the opposite side edge being apertured, all portions of said strip normally lying in the same 50 plane, and the apertured edge portion of the strip being adapted to be bent at an angle to the remainder of the strip in the use of the device.

In testimony that I claim the foregoing 55 as my invention I have signed my name this 24th day of June, 1922.

FRANK STILLWELL.
